STEAM OPERATED LOCOMOTIVE

Lawrence Richardson, Melrose, Mass.

Application June 9, 1937, Serial No. 147,357

16 Claims. (Cl. 105—37)

This invention relates to steam operated locomotives and more particularly to a balanced driving means for such locomotives.

It is well-known in the locomotive art that the maximum safe speed at which a locomotive may travel depends upon, among other things, the degree of pounding of the driving wheels upon the rails. The pounding of the wheels upon the rails is commonly known as "rail-pound" and results from the reaction of the driving impulses of the main connecting rods upon the crank pins of the driving wheels. Such pounding of the driving wheels may be likened to the slap developed by pistons in conventional internal combustion engines due to the angularity of the connecting rods.

Rail-pound is particularly perceptible when a locomotive is running at high speed and, moreover, is objectionable because it essentially limits the maximum speed at which a locomotive may be safely run. Under present travel demands, speed is of paramount importance and, therefore, the problem of reducing rail-pound is very critical.

It is also well-known that excessive rail-pound will place undue strains upon the locomotive frame, and locomotive driving gear in general, and is a constant source of danger in that such pounding may cause rail fracture or breakage, and possible self-derailment of the locomotive.

It is, therefore, the primary object of this invention to provide a locomotive construction in which the rail-pound is reduced to a practical minimum, thus enabling the locomotive to be safely operated at comparatively high speeds. The above is accomplished by providing a locomotive with driving wheels actuated by connecting rod impulses acting in opposite directions and which impulses are synchronized with respect to each other or caused to act so that unbalanced reactions are reduced to a minimum or substantially eliminated in their entirety.

In harmony with the above, another object of the invention is to provide a locomotive construction in which the forces acting upon the driving wheels to turn the same are counterbalanced so that the strain and wear on the parts is reduced to a minimum.

A further object of the invention is to provide a locomotive construction in which the driving forces act in relatively predetermined unison or are counter-balanced so that the pounding of the driving wheels on the rails is substantially less than in prior locomotives of approximately

the same weight having the same size and number of driving wheels.

A still further object of the invention is to provide a locomotive construction in which the movements of the elements of the driving means are so synchronized or counter-balanced that the locomotive may be safely run at speeds higher than locomotives of the same general class without danger of derailment through excessive rail-pound or undue stress on the frame and other working parts due to unbalanced driving forces.

Other and further objects of the invention will be apparent from the following description taken in conjunction with the accompanying drawing, in which:

Figure 1 is a diagrammatic view of a locomotive showing one form of the driving mechanism contemplated by this invention applied thereto;

Figure 2 is an enlarged diagrammatic view of the driving mechanism shown in Figure 1;

Figure 3 is a diagrammatic plan view of the structure shown in Figure 1, but showing the relative positions of the driving wheels upon opposite sides of the locomotive frame;

Figure 4 is a diagrammatic view showing a modification in which the invention is applied to a four-wheel locomotive drive; and

Figure 5 is a diagrammatic view of a further modification of the invention showing the same applied to an eight-wheel drive for locomotives.

Referring now more particularly to Figures 1, 2 and 3 of the drawing, the reference numeral 1 designates a locomotive and the numeral 1^a designates the usual train rails. Three pairs of wheels 2, 3 and 4, respectively, constitute the drivers for said locomotive and engage said rails. These driving wheels are carried at the opposite ends of axles 5, 6 and 7, respectively. The axles 5, 6 and 7 are mounted in the customary journal boxes 8, 9 and 10 operatively associated with a conventional locomotive frame 11.

The frame 11 carries a cylinder 12 adjacent one end thereof and an opposed cylinder 13 adjacent the opposite end thereof. A piston 14 is disposed in the cylinder 12 and is connected to one end of a piston rod 15. The opposite end of said piston rod is connected to a crosshead 16 slidably mounted between crosshead guides 17. The driving wheel 2 is operatively connected with said crosshead by a main connecting rod 19, one end of said connecting rod being directly secured to said crosshead and the other end secured to a crank pin 18 carried by said driving wheel.

The cylinder 13 contains a piston 20 which is

connected to one end of a piston rod 21. The opposite end of the piston rod is connected to a crosshead 22 slidably mounted between crosshead guides 23. The driving wheel 4 is provided with a crank pin 24 which is operatively connected with the crosshead 22 by a main connecting rod 25.

The driving wheel 3 is provided with a crank pin 26 and said pin is connected with the crank pin 18 of the driving wheel 2 by means of a side rod 27.

The journal boxes 9 and 10, which are associated with the axles 6 and 7, are provided with projections 29 and 30, respectively. A bar 28 has its opposite ends pivotally secured to said projections 29 and 30 by pivot pins indicated at 29' and 30', respectively. A lever 31 is pivotally mounted at 32 on the bar 28 at a point midway between the axles 6 and 7. The axis of the pivot 32 is located so that it is in alignment, or in the same plane, with the axes of the axles 6 and 7 as indicated by the line X—X in Figure 2. The object of thus aligning the several axes will be more fully set out hereinafter.

The lever 31 is provided with pivot pins 33 and 34 arranged equidistant from the pivot 32. A link 35 connects the pivot pin 33 with the crank pin 26 of the driving wheel 3, and a second link 36 connects the pivot pin 34 with the crank pin 24 of the driving wheel 4. It will be noted from Figure 2 that the crank pin 24 of the driving wheel 4 leads the crank pins 18 and 26 of the driving wheels 2 and 3, respectively, by 180°. With the parts thus arranged it is apparent that the force exerted by the piston 14 in tending to rotate the driving wheels 2 and 3 is synchronized with an opposite and substantially equal force caused by movement of the opposing piston 20 in tending to rotate the driving wheel 4. The impulses of the pistons 14 and 20 oppose each other by reason of the fact that the crank pins of the driving wheels to which the main rods 19 and 25 are connected are disposed at an angle of 180° relatively to each other. Such relative disposition of the crank pins results in synchronization of the driving forces, and such synchronization is maintained through the pivoted lever 31 and the links 35 and 36 which together serve to constrain the crank pins 18, 26 and 24 of the drivers 2, 3 and 4, respectively, to their predetermined off-set positions.

The description thus far has been limited to the driving mechanism upon one side of the locomotive 1. The driving mechanism upon the opposite side of said locomotive is a duplicate of that already described, except that the crank pins of the driving wheels upon said opposite side lead the crank pins of the driving wheels upon the described side by 90°. This relative disposition of crank pins will be clear from Figure 3. With the crank pins upon the opposite sides of the locomotive arranged as described, any possibility of the driving wheels coming to rest in dead-center position is eliminated. A further advantage of the above arrangement is that the driving impulses upon opposite sides of the locomotive are alternately exerted so that the strain upon the locomotive frame and the various engine parts is much less than would be the case if the driving impulses of the pistons at the respective ends of the engine were exerted in the same direction simultaneously.

The journal boxes 8, 9 and 10 are mounted in a conventional manner in the locomotive frame 11. That is to say, said journal boxes are

mounted with respect to the frame 11 so that they may move vertically a slight amount relatively to said frame and to each other. Such movement is permitted by reason of the fact that the frame 11 is supported by springs (not shown) which allow the respective journal boxes to move relatively toward the frame, as when passing over an irregularity in, or on, a rail, or in passing from one rail onto another rail the end of which is slightly higher or lower than the first-mentioned rail, etc.

Inasmuch as the spring-mounting of the locomotive frame upon the journal boxes is no part of the present invention, the details of such mounting have not been illustrated in the drawing. It is deemed sufficient for present purposes to state that the frame may be supported upon helical springs interposed between the journal boxes and said frame, or said frame may be supported by any one of the various known frame suspension devices employing saddles, leaf springs, links, etc.

Since the journal boxes 8 and 9, which are connected by the bar 28, may move slightly relatively to the frame 11, it is essential that the axis of the pivot 32 of the lever 31 be maintained at all times in a plane common to the axes of the axles 6 and 7. Otherwise, there will be a tendency for the forces acting on the links 35 and 36 connecting the lever 31 to the driving wheels 3 and 4 respectively to cause one or the other of said links to either buckle under compression or to break under tension. The creation of either of such forces in the links 35 and 36 will tend to disrupt the synchronization of the opposed driving forces. However, by mounting the bar 28 relatively to the axles 6 and 7 as described above, the pivot 32 will travel in accordance with the vertical movement of the particular axle, and the relative relationship of the axes of said pivot and said axles will not be disturbed. It will be understood, however, that the vertical movement of the axles 6 and 7 relative to the frame 11 or to each other is of such slight degree that at no time will such movement place any appreciable stress upon the pivot pins 29' and 30'.

In Figure 4 of the drawing, a modification is disclosed which employs four driving wheels instead of six, two driving wheels being disposed on each side of the locomotive. In said modification, a main connecting rod 19' is shown connected to a crank pin 26' which in turn is directly connected by a link 35' to one end of a lever 31'. Thus, the main connecting rod 19' acts directly upon the driving wheel 3' to rotate the same. An opposing main connecting rod 25' is connected to a crank pin 24' of a driving wheel 4'. This crank pin 24' is directly connected by means of a link 36' to the opposite end of the lever 31'. The crank pin 24' leads the crank pin 26' by 180°. It will be understood that in the modification shown in Figure 4, there will be driving wheels upon the opposite side of the locomotive which have crank pins that lead the crank pins 24' and 26' by 90°.

The counter-balancing of the driving forces of the four-wheel driving arrangement shown in Figure 4 is similar to that described above with reference to the embodiment shown in Figures 1, 2 and 3.

In Figure 5, a modification of the supporting means for a lever 31'', corresponding to the lever 31 shown in Figure 2 and the lever 31' shown in Figure 4, is illustrated. In said figure,

the supporting means for the lever 31" is shown in the form of an elongated journal box 37. Said box is made of a length sufficiently great to accommodate axles 6" and 7". The journal box 5 37 is mounted (by means not shown) so that it may move relatively to a locomotive frame on the same principle as the journal boxes 8, 9 and 10, previously described.

The lever 31" is pivoted upon the journal box 10 37 at a point midway between the axes of the axles 6" and 7". It will be particularly noted from Figure 5 that the axes of the pivot 32" is in a plane common to the axes of the axles 6" and 7", as indicated by the line Z—Z. Hence, 15 it will be apparent that as either of the axles 6" or 7" move relatively toward or away from the frame, the pivot 32" will move accordingly and there will be no tendency for links 35" and 36" to buckle or buck each other.

In addition to the above, Figure 5 shows an 20 adaptation of the invention to an eight-wheel locomotive drive. In the form shown, an additional driving wheel 38 is connected by a side rod 39 to the driving wheel 4". It will be clear from a comparison of Figures 2 and 5, that Figure 5 illustrates one manner in which two additional driving wheels may be added to a six-wheel drive such as shown in Figure 2, and an arrangement by which four additional driving wheels may be added to a four-wheel drive such as shown in Figure 4. However, it will be understood that any number of additional driving wheels may be connected to the two driving wheels adjacent the counter-balancing lever by merely extending the side connecting rods to a length such as to accommodate the span between the crank pins of said adjacent drivers and said additional drivers.

It will be further understood that while Figure 5 shows only the driving wheels upon one side of a locomotive, the driving wheels upon the opposite side of said locomotive will be similarly arranged except that their crank pins will be advanced 90° relatively to the crank pins shown in Figure 5. The counter-balancing of the driving forces here is effected by the same principles described in detail in connection with the six-wheel drive shown in Figs. 1, 2 and 3.

In the various forms of the invention described above, the counter-balancing of the forces tending to rotate the driving wheels results in a more efficient operation of the locomotive as a whole and also permits running the locomotive at comparatively high speeds, say of over 100 miles per hour, without danger of straining the parts or causing excessive wear of such parts. Since the thrusts of the main connecting rods upon one side of the locomotive are synchronized by the lever 31, and since said rods 50 exert their thrust alternately to those of the connecting rods upon the opposite side of the locomotive, smoother operation of the driving mechanism is assured. Furthermore, such synchronization of the connecting rod thrusts reduces the pounding of the wheels upon the rails to a practical and safe minimum.

It will be understood that various modifications and equivalent arrangements may be resorted to without departing from the spirit of the invention disclosed herein or from the scope of the appended claims.

What I claim is:

1. A locomotive comprising, a frame, two driving wheels at each side of said frame, each of said 75 driving wheels having a crank pin, a lever dis-

posed between the wheels on each side of said locomotive, rigid means pivotally supporting said lever so that its axis of rotation is always in a plane common to the axes of said wheels and a link directly connecting each end of said levers to said crank pins.

2. A locomotive comprising, a frame, two driving wheels at each side of said frame, each of said driving wheels having a crank pin, the crank pins of the driving wheels on the respective sides of said frame being relatively off-set 180° from each other and the crank pins of the driving wheels on one side of said frame being off-set 90° relative to the crank pins of the wheels on the opposite side of said frame, a lever disposed 15 between the wheels on each side of said frame, pivot means supporting said levers so that the ends thereof are disposed above and below said pivot means, means maintaining the axis of said pivot means in a plane substantially common to 20 the axes of said driving wheels, and means connecting the opposite ends of said levers to said driving wheels on the respective sides of said frame.

3. A locomotive comprising, opposed cylinders 25 at one side thereof, each of said cylinders having a piston therein, two driving wheels disposed between said cylinders, means operatively connecting said pistons with said driving wheels, a pivoted lever disposed between said driving 30 wheels, and means connecting said lever to said driving wheels.

4. A locomotive comprising, a frame, opposed cylinders on opposite sides of said frame, each of said cylinders having a piston therein, at 35 least two driving wheels at each side of said frame between said cylinders, means operatively connecting said pistons with said driving wheels, a lever disposed between two adjacent driving wheels on each side of said frame and means 40 connecting said levers to said adjacent driving wheels.

5. A locomotive comprising, opposed cylinders at one side thereof, each of said cylinders having a piston therein, two driving wheels disposed 45 between said cylinders, means operatively connecting said pistons with said driving wheels, a lever pivotally mounted between said driving wheels, the axis of said pivotal mounting lying in a plane common to the axes of said driving wheels, 50 and means connecting said lever to said driving wheels.

6. A locomotive comprising, a frame, journal boxes associated with said frame, a pair of axles carrying driving wheels at opposite ends thereof 55 journaled in said boxes, a bar connecting the journal boxes at one side of said frame, a lever disposed between said axles and pivotally supported by said bar so that its opposite ends are above and below said bar, and means connecting 60 the opposite ends of said lever to adjacent driving wheels.

7. A locomotive comprising a frame, journal boxes associated with said frame, a pair of axles carrying driving wheels at opposite ends thereof 65 journaled in said boxes, a bar connecting said boxes at one side of said frame, a lever disposed between said axles and pivotally supported by said bar so that its opposite ends are above and below said bar, the axis of said pivotal support 70 lying in a plane substantially common to the axes of said axles, and means connecting the opposite ends of said lever to adjacent driving wheels.

8. Driving means for a locomotive having a frame including, two driving wheels, each of said 75

driving wheels being mounted upon a separate axle, rigid means pivotally connecting said axles, a lever disposed between said driving wheels and pivotally supported by said means, and means connecting said lever to said driving wheels.

9. Driving means for a locomotive having a frame including, two driving wheels, each of said driving wheels being mounted upon a separate axle, rigid means pivotally connecting said axles, a lever disposed between said driving wheels and pivotally supported by said means, the axis of said pivotal support lying in a plane common to the axes of said driving axles, and means connecting said lever to said driving wheels.

10. Driving means for a locomotive including, two driving wheels, each of said driving wheels being mounted upon a separate axle, a longitudinally elongated journal box, the ends of said axles on one side of said locomotive being mounted in said journal box, a lever disposed between said driving wheels and pivotally supported by said journal box so that its opposite ends are above and below said journal box, and means connecting the opposite ends of said lever to said driving wheels.

11. Driving means for a locomotive including two driving wheels, each of said driving wheels being mounted upon a separate axle, a longitudinally elongated journal box, the ends of said axles on one side of said locomotive being mounted in said journal box, a lever disposed between said driving wheels and pivotally supported by said journal box so that its opposite ends are above and below said journal box, the axis of said pivotal mounting lying in a plane common to the axes of the axes of said driving wheels, and means connecting the opposite ends of said lever to each of said driving wheels.

12. In a locomotive, a frame, at least two driving wheels on each side of said frame, axles carrying said driving wheels, drive balancing means disposed between two adjacent axles, a pin mounted in a plane common to the axes of said axles and pivotally supporting said drive balancing means relatively to said axles, and means directly connecting said drive balancing means to at least one of the driving wheels carried by

said adjacent axles on each side of said frame.

13. A locomotive comprising a frame, two axles extending transversely of said frame, a driving wheel on each end of said axles, drive balancing means between said driving wheels, supporting means for said drive balancing means connecting said axles together, a pivot for said drive balancing means carried by said supporting means, the axis of said pivot always lying in a plane common to the axes of said driving wheels, and means connecting said drive balancing means with said driving wheels.

14. A locomotive comprising a frame, a pair of axles extending transversely of said frame, driving wheels upon the ends of said axles, a lever disposed between said driving wheels, supporting means for said lever carried by said axles and including a pivot for said lever, the axis of said pivot being positioned so that it always lies in a plane common to the axes of said driving wheels, and means connecting said lever with said driving wheels.

15. A locomotive comprising a frame, two axles having drive wheels at one side of the frame, each of said driving wheels having a crank pin, drive balancing means between said driving wheels, supporting means for said drive balancing means connecting said axles together, said supporting means including a pivot for said drive balancing means, the axis of said pivot being fixed in a plane common to the axes of said driving wheels, and means connecting said drive balancing means to said crank pins.

16. A locomotive comprising a frame, a pair of axles extending transversely of the frame, a driving wheel on each of said axles at one side of said frame, each of said driving wheels having a crank pin, the crank pin of one of said driving wheels being angularly disposed relatively to the other of said drive wheels, means connecting said axles together, a pivot pin carried by said connecting means, the axis of said pivot pin being positioned so as to always lie in a plane substantially common to the axes of said driving wheels, drive balancing means mounted upon said pivot, and means connecting said drive balancing means to said crank pins.

LAWRENCE RICHARDSON.
